ELECTRICAL METAL FUSING APPARATUS
AND METHODRobert K. Hopkins, New York, N. Y., assignor to
The M. W. Kellogg Co., New York, N. Y., a corporation of Delaware

Application May 21, 1940, Serial No. 336,340

10 Claims. (Cl. 219—8)

This invention relates to the electrical fusion of metals and particularly to the type of operation in which metal is deposited by fusing its constituents at a gap through which electric current is discharged.

In the electrical fusion of metals, wherein metal is fused by the discharge of electric current through a gap, it is the usual practice to employ an electrode, either of metal made up of constituents of the desired metal or of non-consumable material, as one terminus of the gap. The operation is most generally controlled by adjusting the end of the electrode relative to the other terminus of the gap as required to maintain an electrical discharge of substantially constant characteristics. This adjustment is effected by arrangements connected to the electrical discharge circuit which act upon the electrode feed motor, or other equivalent means. By reason of the mass of the moving elements, and their necessary mechanical connections, this manner of control does not result in an instantaneous adjustment so that the characteristics of the electrical discharge and the fusion rate of the electrode are not maintained constant at predetermined values but actually constantly vary, or hunt, about the predetermined values. The variations are such, however, that they average and for any practical run the quantity of metal that will fuse can quite accurately be predicted.

This manner of control, while satisfactory for operations in which the metal fused is derived from the electrode and the base metal, imposes limitations in operations wherein constituents of a final metal of a desired analysis are supplied from sources other than the electrode, or the base metal, or the electrode and the base metal, at rates unaffected by the variations at the gap. In the latter operations, as for instance, those contemplated in my prior Patent No. 2,191,471, it is necessary in order to secure uniform analysis with this type of control, to operate under such conditions that there is always present a sufficiently large body of molten metal to average up the variations in the supply of electrode metal.

The use of this expedient for avoiding non-uniform analysis does not ordinarily affect the efficiency of the process but, in special cases, imposes a limit on the speed at which it can be carried out. Thus, when depositing a thin coating of alloy on a base metal the speed of traverse of the electrode over the base metal and the rate of production of the alloy must be kept down to the values at which a sufficiently large body of molten metal is present to average the varying rate of fusion.

I have found that superior results can be obtained in the general type of operation and the mentioned limitation to the specific operation removed, for all practical purposes, by supplying

the electrode to the gap at a constant rate and adjusting the electrical energy input to the gap as required to fuse the electrode at a constant rate.

5 It is a primary object of the invention to provide a novel method, and novel apparatus for carrying it out in practice, for the electrical fusion of metals wherein metal is fused by the discharge of electric current through a gap between the end on an electrode and a conductive body, the electrode being supplied to the gap at a constant rate and the current discharged at the gap being varied inversely as the resistance of the gap varies to fuse the electrode at a constant rate.

It is also a primary object of the invention to provide a novel method, and novel apparatus for carrying it out in practice, for producing metal of desired analysis by the fusion of its constituents at a gap, between an electrode and a conductive body, through which electric energy is discharged, wherein one or more of the constituents of the desired metal are supplied to the gap in the form of a metal electrode and another or others of the constituents are supplied to be fused with the metal of the electrode, from a source separate from said electrode, the electrode being supplied to the gap at a constant rate, the other, or others, of the constituents being also supplied at a constant rate and the electric current input to the gap being varied inversely as the resistance of the gap varies so as to fuse the electrode at a constant rate whereby the fused metal is made up throughout of a predetermined proportion of the constituents supplied by the electrode and the constituents supplied from the separate source.

It is a further primary object of the invention to provide a novel method, and novel apparatus for carrying it out in practice, for producing metal of desired analysis by the fusion of its constituents at a gap, through which electric current is discharged, between an electrode and a conductive body, wherein one or more of the constituents of the desired metal are supplied to the gap in the form of a hollow metal electrode and another or others of the constituents are supplied in particle form to the gap through the hollow electrode to be fused with the metal of the electrode, the hollow electrode being supplied to the gap at a constant rate, the material in particle form also being supplied at a constant rate and the electric current input to the gap being varied inversely as the resistance of the gap varies to fuse the metal of the electrode at a constant rate whereby a predetermined proportion between the constituents supplied by the hollow electrode and the material in particle form is constantly attained in the fused metal.

The further objects and advantages of the invention will be apparent from a consideration of

the following description, taken with the accompanying drawing, in the single figure of which, is shown a front view of a preferred form of the apparatus of the invention.

The method and the apparatus of the invention are applicable generally to electrical metal fusing operations wherein metal is fused at a gap through which electric current is discharged between an electrode and a conductive body. Thus, they are applicable to seam welding, either of the open or submerged arc type, and when the deposited metal is of substantially the same analysis as that of the metal to be joined or is of different analysis from that of the metal to be joined. They are also applicable to coating or veneering operations, i. e., operations in which composite metal bodies are formed by depositing molten metal of one analysis on a surface of a base metal of a different analysis to unite the metals into an integral structure. Furthermore, they are also applicable to operations in which alloy bodies of a single analysis are produced.

I choose to disclose my invention in detail in connection with the manufacture of an alloy body of a single analysis throughout. Also, while the invention is not limited to the use of a hollow electrode; solid electrodes, composite electrodes, etc., may also be used, I will disclose it in detail in connection with a hollow electrode.

The electrical metal fusing machine 10 with the exceptions of certain elements not necessary to the present disclosure approximates that disclosed in my prior Patent No. 2,191,476 and, hence, the common elements will not be gone into in detail here.

Machine 10 is supported on a suitable structure 11 for movement in all directions over mold 12. Mold 12 is shown as a water cooled metal mold, preferably of copper; however, any preferred mold suited to the particular operation may be employed, thus, even a refractory mold may be employed. When the invention is used in seam welding or in the coating of metal bodies, the bodies to be united or the base metal to be coated is substituted for mold 12.

Within housing 13 is the tube forming mechanism that converts flat strip 14 into the hollow pipe like electrode 15. Strip 14 is made of a constituent, or constituents, of the ultimately desired metal and is conveniently carried on reel 16. The formed hollow electrode passes from the tube forming mechanism through a contact nozzle 17 from whence it proceeds towards mold 12. A vibrator device 18 may be provided adjacent nozzle 17 to prevent clogging of the end of hollow electrode 15.

The tube forming mechanism is driven by shaft 19 that is connected by gears, in gear-box 20, to the shaft 21 of motor 22. Motor 22, since it operates the tube forming mechanism, is the feed motor for hollow electrode 15 and in any particular operation is operated at a constant speed. To give the apparatus a degree of flexibility, so that it may be used generally in the type of operation contemplated, motor 22 may be of such kind that it can be operated at any speed within a predetermined range of speeds, or it may be a single speed motor and a speed changing device, not shown, provided between it and shaft 19 of the tube forming mechanism.

Contact device 17 is connected through cable 23 to one side of the output of generator 24, the other side of the output is grounded through cable 25 to metal mold 12. Generator 24 may be

such as to generate A. C. or D. C. current, as preferred and will normally be driven as by motor 26.

The field windings of generator 24 are tapped by wires 27 and 28 so as to place variable resistance device 29 in the field circuit. The arrangement is preferably such that device 29 is in series with the field windings. Device 29 may be of any preferred form but must function to cut resistance into the field circuit as the voltage across the output cables increases and cut resistance out of the field circuit as the voltage across the output cables decreases. A number of commercial devices suited for this purpose are available. I have shown schematically a device 29 that will function as required.

Device 29 includes a resistance 30 that is connected to wire 28. The contact end of pivoted contact bar 31 is adapted to make contact with resistance 30 as it is moved over the surface of resistance 30 to change the ohmic value of the resistance in the field circuit to thus alter the field excitation and, consequently, the current output of generator 24. Contact bar 31 is connected at its pivot to wire 27. The other end of bar 31 is connected by suitable linkage to the metal core 32 of solenoid 33. Wires 34 and 35 shunt solenoid 33 across cables 23 and 25. A spring 36 constantly tends to pull contact bar 31 to the zero resistance contact point.

On a platform 37 above housing 13 are mounted metering devices 38. These devices are preferably of the type shown and described in my prior Patent No. 2,174,175, although metering devices of any comparable type may be employed. Six devices 38 have been shown but a greater or lesser number may be used as required. Each device 38 is provided with a hopper 39 in which is placed the particular granular material to be metered by the particular device. The metered materials pass into a common hopper 40 from whence they pass through tube 41 into the formed hollow electrode 15. The granular materials are alloys or pure metals made up of constituents of the final desired metal.

Metering devices 38 are driven by shaft 42 that is connected to the output of the combined clutch and speed changer box 43. The input of box 43 is connected to the shaft of motor 44. Motor 44 is of the constant speed type so that the materials metered are supplied into hollow electrode 15 at a constant rate throughout the operation of the apparatus.

In the deposition of ferrous alloys such as the chrome-irons or the chrome-steels, chrome-nickel steels, etc., strip 14 will usually be a low carbon iron or steel, Armco iron, for example, and the granular materials supplied into hollow electrode 15 ferro-alloys such as ferro-chrome, ferro-manganese, etc., or pure metal such as nickel, etc.

In the production of an alloy ingot of a desired analysis, knowing the analysis of the chosen material of strip 14 as well as the analysis of the chosen granular materials to be supplied into hollow electrode 15, and the preferred fusing capacity of the apparatus, it is a simple matter to determine the metering rates of the granular materials and the feed rate of hollow electrode 15. Experience will indicate in each case the preferred resistance across the current discharge gap and with this established the necessary current output of generator 24 is easily determined. With this information metering devices 38 and their drive, the tube forming mechanism and its

drive, and generator 24 can be set to give the required results. Generator 24, however, will be so adjusted that contact bar 31 during normal operation, will not be on the zero resistance contact but preferably will be between the ends of resistance 30.

After the necessary settings and adjustments have been made, mold 12 is positioned and the water flow around it started. A plug of metal, preferably of the desired analysis is placed in 10 the bottom of mold 12. To facilitate starting, the hollow electrode is fed almost to the surface of the metal plug and a wad of steel wool, or similar arc starter interposed between the electrode and the plug. The electrode end, as well as the bottom of the mold, are then covered with a deep 15 blanket of protective flux 45. The motor 28 is the energized and the operation commenced, after the motor-generator set has come up to speed, by closing the generator output circuit 20 and the circuits of motors 22 and 44.

The initial current surge destroys the arc starter to establish a discharge gap, beneath flux 25 blanket 45, between the electrode and the metal plug. As the initial flow is at short circuit, the initial energization of solenoid 33 will be insufficient to pull contact arm 31 off the no 30 resistance stop, however, as the gap forms the voltage rises and increases the energization of the solenoid so that contact arm will be moved over the resistance 30 to cut it into the field circuit and thus reduce the current output of the generator. This movement of bar 31 will continue until the gap is brought to the predetermined 35 ohmic value; when the rate of fusion of electrode 15 will equal its rate of speed.

During the operation, for various causes, the 40 resistance of the gap will change. When such changes occur the voltage in the energizing circuit of solenoid 33 will change and bar 31 will be moved to change the resistance in the generator field circuit to vary the current output inversely as the resistance of the gap varies. Thus, if the 45 resistance of the gap increases, bar 31 will move to cut more resistance into the generator field circuit to diminish the current output until the resistance of the gap is again at the predetermined value when the decrease in voltage in the 50 circuit of solenoid 33 will cause bar 31 to return to its previous position. If the resistance of the gap increases bar 31 will move to remove resistance out of the generator field circuit to increase the current output until the predetermined 55 resistance of the gap is reestablished when bar 28 will move back to its previous position. In this manner the fusion rate of hollow electrode 15 will be maintained constant for the full period of operation.

Since the granular materials are fed into hollow electrode 15 at a constant rate, the constituents supplied by hollow electrode 15 and the granular materials will constantly be fused at the gap in the predetermined proportions and the final metal will be of uniform analysis throughout. Furthermore, this result will be obtained without the necessity of maintaining a sufficiently large pool of molten metal to average varying 60 rates of supply of the constituents.

In A. C. operations it will sometimes be preferable to substitute for generator 24 and its associated devices and arrangements, a transformer of low reactance. The transformer should preferably be so arranged that its reactance can be adjusted to the best values for selected discharge voltages. When a low reactance trans- 75

former is employed the reactance of the cables connecting the output to contact device 17 and to mold 12 should be kept to a minimum. Such a transformer, properly adjusted, and with an output circuit of low reactance, will automatically vary the current output inversely as the resistance of the discharge gap varies as required, to fuse electrode 15 at a constant rate.

I claim:

1. In metal fusing apparatus, means for feeding a metal electrode at a substantially constant rate toward a conductive body for fusion by the discharge of electric current through a gap between its end and the conductive body, electric current supply means connected to said electrode and said body for discharge of electric current through said gap, and means for altering the electric current supply as required to maintain the fusion rate of said metal electrode substantially constant.

2. In metal fusing apparatus, means for feeding a metal electrode at a substantially constant rate toward a conductive body for fusion by the discharge of electric current through a gap between its end and the conductive body, electric current supply means connected to said metal electrode and said body for discharge of electric current through said gap, said electric current supply means being adapted at a predetermined resistance value of said gap to supply electric current at the rate required to fuse said metal electrode at a rate equal to its rate of supply and means effective to vary the rate of supply of electric current inversely as the resistance value of said gap varies to maintain the fusion rate of said metal electrode substantially constant.

3. In metal fusing apparatus, means for feeding a metal electrode at a substantially constant rate toward a conductive body for fusion by the discharge of electric current through a gap between its end and the conductive body, electric current generator means having one side of its output connected to said metal electrode and the other side connected to said conductive body for discharge of electric current through said gap, said generator means being adapted at a predetermined resistance value of said gap to supply electric current at the rate required to fuse said metal electrode at the rate supplied, and means effected by electric energy variations in the output circuit of said generator means for varying the electric current output of said generator means as required to substantially constantly fuse said metal electrode at the rate supplied.

4. In metal fusing apparatus, means for feeding a metal electrode at a substantially constant rate toward a conductive body for fusion by the discharge of electric current through a gap between its end and the conductive body, an electric current generator including an excitable field having one side of its output connected to said metal electrode and the other side connected to said conductive body for discharge of electric current through said gap, said generator being adapted at a predetermined resistance value of said gap to supply electric current at the rate required to fuse said metal electrode at a predetermined rate, and means actuated in accordance with electric energy variations in the output circuit of said generator for varying the excitation of said field inversely as the resistance of said gap varies to vary the electrical output of said generator as required to substantially constantly fuse said metal electrode at the predetermined rate.

5. In metal fusing apparatus, means for feed-

ing a metal electrode at a substantially constant rate toward a conductive body for fusion by the discharge of electric current through a gap between its end and the conductive body, an electric current generator having one side of its output connected to said metal electrode and the other side connected to said conductive body for discharge of electric current through said gap, said generator including an excitable field and a variable resistance means for varying the excitation of said field, said generator being adapted at a predetermined resistance value of said gap to supply electric current at the rate required to fuse said metal electrode at a predetermined rate, and means actuated in accordance with electric energy variations in the output circuit of said generator operable to vary the ohmic value of said variable resistance means as the resistance of said gap varies to thereby vary the output of said generator as required to substantially constantly fuse said metal electrode at the predetermined rate.

6. In apparatus of the character described, means for feeding a metal electrode made up of constituents of the desired metal at a substantially constant rate toward a conductive body for fusion by the discharge of electric current through a gap between the end of the metal electrode and the conductive body, said feeding means being adapted to feed said electrode at a substantially constant predetermined rate, means for supplying further metal made up of constituents of the desired metal to the gap at a constant rate to be fused with the metal of the electrode, electric current supply means connected to said metal electrode and said conductive body for discharge of electric current through said gap, said electric current supply means being adapted to supply electric current at the rate required to fuse said metal electrode as supplied at a predetermined resistance value of said gap, and means effective to vary the current supplied by said current supply means inversely as the resistance of said gap varies whereby said metal electrode is fused at a substantially constant rate and a predetermined proportion between the constituents of the desired metal supplied by said metal electrode and said further metal is maintained substantially constant throughout the operation of the apparatus.

7. In metal fusing apparatus, means for feeding a hollow metal electrode made up of constituents of the desired metal at a substantially constant rate toward a conductive body for fusion by the discharge of electric current through a gap between the end of the metal electrode and the conductive body, said means being adapted to feed said hollow electrode at a substantially constant predetermined rate, means for supplying metal made up of constituents of the desired metal in granular form through said hollow electrode to be fused at said gap with the metal of said hollow electrode, said supplying means being adapted to supply said metal in granular form at a substantially constant predetermined rate, electric current supply means connected to said hollow electrode and said conductive body for discharge of electric current through said gap, said electric current supply means being adapted at a predetermined resistance value of said gap to supply electric current at the rate required to fuse said hollow metal electrode

as supplied and means effective to vary the current supplied by said current supply means inversely as the resistance of said gap varies whereby said hollow metal electrode is fused at a substantially constant rate and a predetermined proportion between the constituents of the desired metal supplied by said hollow metal electrode and said granular metal is maintained substantially constant throughout the operation of the apparatus.

5 8. In the electrical fusion of metals wherein metal is fused by the discharge of electric current through a gap between the end of metal electrode and a conductive body, the steps comprising, feeding a metal electrode at a constant rate to the gap, supplying electric current to the gap to fuse the electrode at the rate supplied when the resistance of the gap is at a predetermined value, and varying the current supply inversely as the resistance of the gap varies to maintain the fusion rate of the metal electrode substantially constant.

15 9. In the electrical fusion of metals wherein a metal of desired analysis is produced by the fusion of its constituents at a gap through which electric current is discharged between the end of a metal electrode and a conductive body, the steps comprising, feeding a metal electrode made up of constituents of the desired metal at a constant rate to the gap, supplying metal made up of constituents of the desired metal from a source separate from the metal electrode at a constant rate to be fused with the metal of the electrode, the rate of feed of the electrode and the rate of supply of the metal from the separate source being so chosen that the constituents of the desired metal are constantly supplied in the required proportions, supplying electric current for discharge through the gap at a rate to fuse the metal electrode as presented when the resistance at the gap is a predetermined value, and adjusting the current input as the resistance at the gap varies to substantially constantly fuse the metal electrode as presented.

25 10. In the electrical fusion of metals wherein a metal of desired analysis is produced by fusion of its constituents at a gap through which electric current is discharged between the end of a metal electrode and a conductive body, the steps comprising, feeding at a substantially constant rate to the gap, a hollow metal electrode made up of constituents of the desired metal, discharging electric current through the gap between the end of the metal electrode and the conductive body, the electric current input to the gap normally being such that the hollow metal electrode is fused at the rate fed when the gap is of a predetermined resistance, varying the electric current input to the gap inversely as the resistance at the gap varies to substantially constantly fuse the electrode at the rate fed, and supplying at a constant rate through the hollow metal electrode metal in granular form made up of constituents of the desired metal to be fused at the gap with the metal of the hollow metal electrode, the rate of feed of the hollow metal electrode and the rate of supply of the metal in granular form being such that the constituents of the desired metal are substantially constantly fused at the gap in the proportions required in the desired metal.

ROBERT K. HOPKINS.

CERTIFICATE OF CORRECTION.

Patent No. 2,300,670.

November 3, 1942.

ROBERT K. HOPKINS.

It is hereby certified that error appears in the printed specification of the above numbered patent requiring correction as follows: Page 5, first column, line 36, for the word "speed" read --feed--; line 51, for "increases" read --decreases--; page 4, first column, line 23, claim 6, for "apparatus of the character described" read --metal fusing apparatus--; and lines 29, 30 and 31, same claim, strike out "said feeding means being adapted to feed said electrode at a substantially constant predetermined rate,"; and lines 57, 58 and 59, claim 7, strike out "said means being adapted to feed said hollow electrode at a substantially constant predetermined rate,"; and that the said Letters Patent should be read with this correction therein that the same may conform to the record of the case in the Patent Office.

Signed and sealed this 12th day of January, A. D. 1943.
